(No. Model.)

F. H. SMITH.

TUBE WELL.

No. 358,578.

Patented Mar. 1, 1887.

UNITED STATES PATENT OFFICE.

FREDERICK H. SMITH, OF KANSAS CITY, MISSOURI, ASSIGNOR TO ENGLISH BROS., OF SAME PLACE.

TUBE-WELL.

SPECIFICATION forming part of Letters Patent No. 358,578, dated March 1, 1887.

Application filed October 9, 1886. Serial No. 215,773. (No model.)

To all whom it may concern:

Be it known that I, FREDERICK H. SMITH, of Kansas City, Jackson county, Missouri, have invented certain new and useful Improvements in Tube-Well^s, of which the following is a full, clear, and exact description, reference being had to the accompanying drawings, forming a part hereof.

This invention relates to devices for locking check-valves and screens in the pumping-cylinders of tube-wells, and the object which I seek to accomplish by it may be briefly recited as follows: to construct a driving-shoe from ready-made materials, so that its cost will be comparatively small; to so construct said shoe that it will afford a solid bearing for the screen-coupling and prevent it from being driven through and lost, and yet at the same time permit the bit of a drill that is of the same diameter as the screen-coupling to pass through; to construct a check-tube with improved devices for locking it in place in the cylinder by means of rotary movement of the plunger-rod, and to provide the shoe, the screen-coupling, and the check-tube with suitable devices for holding them from turning while the check-valve is being fixed in the cylinder.

In the drawings, which illustrate the manner of carrying out my invention, Figure 1 is a sectional elevation of my cylinder and driving-shoe, the section being taken on line X X, Fig. 3. Fig. 2 is a sectional view of the check-valve complete and in proper position upon the screen-coupling, the section being taken on line y y, Fig. 4. Fig. 3 is a transverse section through the shoe on line X X, Fig. 1. Fig. 4 is a similar section through the junction of the check-tube and the screen-coupling on line y y, Fig. 2; and Fig. 5 is a detail elevation of, say, a portion of the check-tube and the screen-coupling, which I exhibit merely for the purpose of showing more plainly the form of the interlocking joints used in making up my invention.

In the ordinary shoe for tube-wells, having an annular shoulder projecting from its inner surface for the screen-coupling to rest upon, it is impossible to pass a drill or other tool through the shoe that is of the same size or larger than the bore of the cylinder, because the cutting-bit of the drill will strike upon the

said shoulder and prevent the passage. To illustrate the matter, I will say that it is sometimes necessary to pass an expansion-drill through the shoe, which with the old-style shoe it is impossible to do, as the hinged cutters are quite certain to strike the shoulder on the downward stroke and prevent the drill from passing below the shoe. In my construction, however, I take an ordinary pipe-coupling having suitable diameter to screw on the outside of the cylinder A, and screw firmly into one end of it a short piece of ordinary pipe, B³, (which I will designate as the "throat" of the shoe.) Then I bore or turn out the end of the coupling in which the throat-piece has been inserted, so that it will flare outwardly, as shown, and thereby form a shoe having the usual form and the ordinary shoulder; but the shoe as thus constructed would not allow the passage of a drill, as before explained, so I next proceed to cut out in some way a pair of opposite recesses, B, from the inner surface of the said throat-piece. This I prefer to do by means of a milling-machine or a key-seat-cutting machine. Cutting out these recesses thus increases the diameter of the throat of the shoe a considerable amount in the place where the recesses are located, and consequently a drill or other tool that is somewhat flat and thin can be passed through, or it can be worked up and down in the throat until a hole is formed below the shoe, as may be required.

In this connection I may say that the shoe G, or a shoe having the same form, can be cast in one solid piece with the recesses B, and all complete, if desired; but I would prefer the before-mentioned construction, because of its small cost and by reason of the materials being always near at hand.

The upper end of the screen K is screwed into the screen-coupling H in the usual manner; but the lower edge of said coupling is provided with a pair of oppositely-located recesses, t, the formation of which engenders the creation of a pair of oppositely-located projections or tongues, t¹; and it is obvious that when the screen-coupling is located in its place in the cylinder its lower edge will rest upon the shoulders d. Now, upon turning the screen-coupling a little the projections t will

drop into and engage the recesses B, as shown, thus preventing the further turning of the said coupling unless the entire shoe and cylinder be rotated with it; but the screen-coupling and the shoe can be separated, at any time that it may be necessary to remove said screen, by simply raising the said screen straight up.

For the purpose of preventing the check-tube L' from turning while the rubber packing-ring L is being expanded, I also make the upper end of the said coupling in the same manner—that is, I provide it with a pair of oppositely-located projections, t, which are located directly above the recesses t' in the lower edge. Recesses t', also oppositely located in the lower edge of the check-tube, engage the projections on the upper edge of the screen-coupling.

The body portion of the check-tube L' is provided with a screw-thread upon its outer surface, which is engaged by the internally-threaded body of the valve-cage b; and the upper edge of said check-tube is provided with a rounded seat, e, for the valve e', the stem a of the valve depending downwardly into the water-passage of the tube.

Encircling the body of the check-tube is the rubber packing-ring L, which flares outwardly from its inner surface, and which is provided with a rounded upper edge, a', for the purpose of preventing friction with the sides of the pipe and cylinder when the check-valve is to be removed therefrom. The rounded edge a', coming in frictional contact with the sides of the pipe, will not be so liable to damage and to be torn as would the edge of a ring of ordinary construction.

The lower edge of the cage b is provided with a cone, e'', or it may be said to flare outwardly and upwardly, and said cone is adapted to engage the flaring surface of the packing-ring L when said cage is screwed downwardly upon the check-tube, and thereby cause the said ring to be expanded forcibly against the sides of the cylinder A, thus securely locking the entire check-valve securely in place, and forming a water-tight joint between the valve and the sides of the cylinder.

Of course, by unscrewing the cage from the check-tube at any time, the check-valve can be removed from its place, and in pulling the valve upwardly the packing-ring L will be raised, with the other devices with which it is connected, by reason of its lower edge resting upon the large shoulder 40, formed upon the check-tube L'.

For the purpose of placing the check-valve in the pipe or cylinder of a tube-well, I provide the upper portion of the cage b with a left-hand thread, 20, which is engaged by a similar thread on the lower end of the pump-rod E, and with this construction the operation of placing the check-valve in the cylinder will be as follows: First, the screen K is dropped in the pipe with coupling H attached thereto. Then the rod E is screwed into the

cage b, and the check-valve entire is lowered into the pipe. Of course the rod E should be screwed into the cage as tightly as possible, so that it will not be disengaged therefrom in 70 screwing down the cage upon the check-tube. Then by turning the rod around slowly the screen-coupling H will find its seat in the throat of the shoe, and so be prevented from turning, and also in a like manner the recesses 75 in the lower edge of the check-tube will engage the projections t on the upper edge of the said coupling, and the whole will be practically locked together and will be prevented from turning, thereby allowing the cage to be 80 screwed firmly to place upon the check-tube and expanding the packing-ring L tightly against the sides of the cylinder.

The cage is not permitted to be screwed too far down upon the check-tube by reason of 85 the shoulder 12 coming in contact with the upper edge or shoulder, 10, formed upon the upper edge of the said tube, and when these two shoulders come in contact the rod E may be unscrewed from the cage and withdrawn from 90 the pipe. The thread on the end of the rod E being a left-handed one, it will only be necessary to continue turning said rod toward the right hand to detach it from the cage.

When the screen-coupling is in place in the 95 cylinder and in the shoe, the upper side of the recesses or the lower edge, 14, of the said screen will rest upon the shoulders d in the throat-piece of the shoe.

Having thus described my invention, what 100 I claim is—

1. A driving-shoe for tube-wells, having shoulders d for supporting the screen-coupling, and provided with opposite recesses B, for the purpose set forth.

2. A driving-shoe for tube-wells, composed of a main body threaded internally its entire length and a throat-piece screwed within the main body, substantially as set forth.

3. The herein-described driving-shoe for 110 tube-wells, consisting of a main body threaded internally its entire length, throat-piece B', having shoulders d and recesses B, and the end of both body and throat-piece turned or bored to flare outwardly, substantially as set 115 forth.

4. The screen-coupling H, provided with opposite recesses t' in its lower edge and with recesses t in its upper edge, substantially as 120 described.

5. The packing-ring L, provided with a rounded upper edge, a', for the purpose described.

6. Cylinder A, shoe G, screen-coupling H, check-tube L', and cage b, all constructed and 125 combined substantially as described.

In testimony whereof I affix my signature in presence of two witnesses.

FREDERICK H. SMITH.
